UNITED STATES PATENT OFFICE.

ALBERT LORSCH, OF NEW YORK, N. Y.

DESIGN FOR A WATCH-CASE OR LOCKET.

SPECIFICATION forming part of Design No. 16,808, dated July 20, 1886.

Application filed February 20, 1886. Serial No. 192,768. Term of patent 31 years.

To all whom it may concern:

Be it known that I, ALBERT LORSCH, of the city, county, and State of New York, have invented a new and original Design for Watch-cases or Lockets, of which the following is a full, clear, and exact description, reference being had to the accompanying drawings, making part of this specification, in which—

Figure 1 represents a front elevation of a watch-case made according to my design, and Fig. 2 is a horizontal section of the same on line xx , Fig. 1, drawn on a larger scale.

Similar letters of reference indicate corresponding parts.

The design relates to watch-cases and lockets; and it consists of a watch-case or locket provided with a countersunk letter, the depressed portions of which are ornamented with jewels that are flush with the surface of the case.

In the drawings, A represents the face or back of a watch-case or locket, and B a depressed letter, of a Roman or other alphabet,

which is arranged at the center of the face or back of the case or locket. The depressed portion of the letter B is studded with diamonds or other precious stones, C, which are flush with the surface of the case or locket. The depressed portion of the letter B is finished in dark enamel, so as to set off the diamonds or other stones in bold relief.

Having thus described my design, I claim as new and desire to secure by Letters Patent—

The design, substantially as herein shown and described, for a watch-case, consisting of a depressed or sunken letter in the outer surface of the back of the watch-case or locket, and of jewels in the recess, the points of the jewels being flush with the face of the back.

In testimony that I claim the foregoing as my invention I have signed it this 12th day of December, 1885.

ALBERT LORSCH.
